UNITED STATES PATENT OFFICE.

JOSIAH PARTRIDGE, OF NEW YORK, N. Y.

DESIGN FOR ROCKING-CHAIRS.

Specification forming part of Design No. **11,511**, dated November 18, 1879; application filed October 20, 1879.
[Term of patent 7 years.]

To all whom it may concern:

Be it known that I, JOSIAH PARTRIDGE, of the city, county, and State of New York, have originated a new and useful Design for a Rocking-Chair; and that the following is a full, clear, and exact description of the same, reference being had to the accompanying drawing, making part of this specification.

A represents the back posts of the rocking-chair. These back posts have the outline of a curve of one radius from their upper to their lower ends, the curve on their front edge or face being convex, and the curve on their rear edge concave. The front edges or faces of these posts are ornamented by moldings *a*, extending from their upper ends to the seat *B* of the chair. The frame of this seat is circular, and is also ornamented on its edge by a molding, *b*.

From the back posts, *A*, extending in a horizontal position, are arms *C*. These arms are curved, as is shown in the drawing, and the edges of these arms are also ornamented by a molding, *c*. To these arms, and at right angles to the same and extending to the seat *B*, are cylindrically and ornamenteally turned posts *D*. To the front of the seat *B*, and beneath the front edge of the same, is a curved cleat, *d*.

Extending from one back post, *A*, to the other, and at or near their top, is a head-piece, *E*. This head-piece is in the form of an open frame with curved sides, and with ornamental posts *e* passing at intervals vertically across the opening of the frame. To the

upper edge of this head-piece or frame are fixed ornamental balls *f*, in line with each of the ornamental posts *e*, the entire design of the head-piece being somewhat that of a coronet. The lower part of the back posts, *A*, near the seat *B*, is spanned by a bar, *E'*, which is curved to the same radius as the head-piece *E*. The front legs, *F*, and back legs, *G*, are connected to each other by rockers *H* and braces or rounds *g* and *h*, the rounds *g* being ornamenteally turned, as shown in the drawing.

What I claim as my invention is—

A design for a rocking-chair in which the back posts have the outline of a single curve from end to end, the front edge or face of the posts being ornamented by a molding formed thereon, the arms of the chair extending at right angles to the back posts, being variously curved, with their edges likewise ornamented by moldings, combined with cylindrically ornamented posts which support the arms, and a seat of circular form for the chair, with a frame which has its edge also ornamented by a molding, and a head-piece, consisting of an arched open frame, with ornamental posts *e* vertically crossing the open space of the frame and ornamented by balls *f* on the upper edge of the frame, and with ornamental turned front legs, *F*, substantially in the manner described.

JOSIAH PARTRIDGE.
